UNITED STATES PATENT OFFICE.

CHARLES B. REYNOLDS, OF PANORA, IOWA.

END-GATE.

1,256,257.

Specification of Letters Patent. Patented Feb. 12, 1912.

Application filed January 3, 1917. Serial No. 140,423.

To all whom it may concern:

Be it known that I, CHARLES B. REYNOLDS, a citizen of the United States, residing at Panora, in the county of Guthrie and State 5 of Iowa, have invented certain new and useful Improvements in End-Gates, of which the following is a specification.

The present invention relates to new and useful improvements in end gates for wagons 10 or the like.

The primary object of the invention is the provision of an end gate having a removable section, with means for actuating the same and locking it in closed position.

15 A further object of the invention is the provision of an end gate which will be simple and inexpensive to manufacture, reliable and efficient in use, and readily operated.

With the above and other objects in view 20 the present invention resides in the novel features of construction, formations, combinations and arrangements of parts to be hereinafter more fully described, claimed and illustrated in the accompanying drawings forming a part of the present application and in which;

Figure 1 is a transverse sectional view taken through the end gate;

Fig. 2 is a rear elevation of a wagon body 30 with the end gate in position;

Fig. 3 is a horizontal sectional view taken through the end gate and adjacent portions of a wagon body;

Fig. 4 is a detail perspective view of one 35 of the main straps;

Fig. 5 is a similar view of one of the locking straps, and

Fig. 6 is a detail sectional view taken on the lines 6—6 of Fig. 3.

40 Referring to the accompanying drawings by corresponding characters of reference throughout the several views, the numeral 7 designates in general a wagon body comprising a bottom 8 and opposite sides 9. The 45 end of the wagon body is closed by an end gate 10 which consists of upper and lower plates 11 and 12 the former of which is cut out to receive the latter.

A pair of straps 12' are secured to the rear 50 face of the end gate 10 adjacent its opposite ends and are formed with upper bearings 13 adapted to receive an attaching rod 14 by means of which the said end gate is secured in its normal position. These straps extend vertically adjacent the opposite ends of 55 the cut out portion 15 in which the section

12 is located, and extend into said cut out portion 15 at the upper corners thereof as shown at 16, to prevent the outward movement of the upper edge of the section 12. 60 The lower ends of these straps 12' are bent laterally as at 17 forming stops which engage the lower edge of the member 12 and prevent the outward movement of the lower edge of the said section. 65

Similar straps 18 are secured to the rear side of the section 12 adjacent the ends thereof and are offset at their lower ends as at 19 forming depending locking fingers 20 which engage the before mentioned fingers 17 when the section 12 is in the position shown in 70 Figs. 1 and 2 thereby firmly locking said section against undesired movement.

A bail 21 of the usually curved formation is offset adjacent its lower ends as at 22 and 75 held in bearings 23, while the lower terminals thereof are bent laterally as at 24 and engaged in bearings 25 formed in the straps 18. During the manipulation of this crank formation 26 at the lower ends of the bail 21, 80 as the upper portion 27 of the bail is swung downwardly, the section 12 is rocked upwardly and inwardly passing into the wagon, whereupon the contents will be discharged through the cut away portion 15 in the section 85 11.

A suitable retaining clip 28 is provided for retaining the bail in the position shown in Figs. 1 and 2 while a suitable handle 29 is secured to the section 12 by means of 90 which the same can be manually operated if desired.

In order to reinforce the end gate 10, suitable strips 30 may be secured to the inner side of the same, and the fastenings which 95 secure the same to the end gate may be extended to fasten the straps 12' in position.

From the foregoing description taken in connection with the accompanying drawings it will be manifest that an end gate is provided which will fulfil all of the necessary requirements of such a device, and it should be understood in this connection that various minor changes in the specific details of construction can be resorted to within the scope 105 of the appended claim, without departing from the spirit or sacrificing any of the advantages of the invention.

Having thus fully described the invention what I claim is new and desire to protect 110 by Letters Patent is:

In an end gate, a pair of plates, one plate

being cut away and the other plate fitted in the said cut away portion, straps secured to the adjacent ends of the plates, an interlocking engagement between said straps, a bail
5 having cranks thereon secured to the straps of the opposite plates whereby when said bail is swung downwardly one plate will be rocked away from the cut away portion of

the other plate, and a securing rod passing through the straps of one of the plates. 10

In testimony whereof I affix my signature in the presence of two witnesses.

CHARLES B. REYNOLDS.

Witnesses:

J. W. REYNOLDS,

T. R. SWANSON.
